UNITED STATES PATENT OFFICE.

WILLIAM D. FRASER, OF CLEVELAND, OHIO.

MACHINE FOR RENEWING CARTRIDGES.

Application filed February 4, 1918. Serial No. 215,256.

To all whom it may concern:

Be it known that I, WILLIAM D. FRASER, a citizen of the United States, residing at Cleveland, in the county of Cuyahoga and 5 State of Ohio, have invented certain new and useful Improvements in a Machine for Renewing Cartridges, of which the following is a specification.

This invention pertains to a machine for 10 renewing used rifle cartridges, and my general object is to provide a simple and effective device which will enable anyone to re-size a used cartridge shell and de-cap it and then re-prime and reload it for use again.

15 My first object is to provide means capable of reducing an expanded shell to its original diameter so that it may be introduced as freely into the breech of a gun as in the first instance. My second object is to furnish 20 means to de-cap or remove the dead primer in the old cartridge during the re-sizing operation on the shell. My third object is to supply means for pressing new caps or 25 primers into the re-sized shells. My fourth object is to construct the machine so that the loading of the shells with powder may be accurately and quickly accomplished, and 30 fifth object is to equip the machine with means to press the bullets tightly into the filled and primed shell.

In the accompanying drawings, Fig. 1 is a vertical sectional elevation of the machine 35 on line 1—1, Fig. 3, looking to the right. Fig. 2 is a plain elevation of the complete 40 machine with the turret in the front and otherwise from the same point of view as Fig. 1. Fig. 3 is an elevation of the machine at right angles to Fig. 2, and sectioned through the turret and portions thereof having to do with removal of the cap or primer 45 from the empty shell. Fig. 4 is a plan view partly in section on a line corresponding substantially to line 4—4, Fig. 3. Fig. 5 is an elevation of a portion of the body of the 50 machine and a section of the turret showing the operation of inserting a bullet in an otherwise renewed shell.

In detail, the invention consists of a tubular body or standard 2 having a suitable 55 base and means supported thereon to do all the work. These means comprise a rack-

bar or shaft 3 of the plunger type slidably mounted in the said standard and engaged by a pinion 4 located in a side recess at about the middle of the standard lengthwise 55 and controlled by a lever or levers 6 on the stem 5 of said pinion. This arrangement is one means of applying power, but I do not wish to limit myself thereto.

The said shaft or plunger 3 is slideable up 60 and down within limits and has a somewhat refined adjustment or stop in its descent for reasons presently to be seen and which involve a screw 7 set into the upper end of the said plunger and a pair of nuts 8 engaging 65 said screw and bearing upon the top of the standard 2, thus enabling the operator to vary and fix the descent of the plunger to any predetermined distance as the operating means may require and which involve the 70 compression or contraction of the empty and more or less expanded shell preparatory to further operations; the removal of the dead cap or primer from the shell, and the insertion of a new primer before the 75 shell is refilled with powder. Therefore, the standard 2 is provided lengthwise with slots 80 9, 10 and 11, the two slots 10 and 11 being one above the other, and the slot 9 being in the upper portion of the standard in a plane a right angles to the slots 10 and 11, see Fig. 2. The standard is also provided with a projection 13 in line with and between the slots 10 and 11 in which a die *d* is supported. 85 Studs or arms 14 and 15 respectively, are set into plunger 3 and project through slots 10 and 11 and their function is to force an empty shell *S* into and out of die *d*. The said die is fixed at its lower end within a collar 16 which is seated within a recess 90 in the projection 13 having a central opening at its bottom, and collar 16 is locked in place by a set screw 19. The die is a tubular member shaped internally according to the shape and size of the shell that is used for the time being, whether it be of a Springfield rifle or another make or kind or a different kind of arms, and therefore is interchangeable and corresponds substantially to the 95 length of the shell so that when the shell is forced into the same from above by the flat-sided arm 14 and the said arm reaches 100

the top of the die at the end of its stroke the shell will also be pressed inward to its limit. The downward movement of said arm is fixed by the nuts 8 at the top of plunger 3 engaging the top of the standard, and both ends of the die *d* are open to entrance from above and below.

The previously used shells being more or less expanded as a result of firing it follows 10 that they must be compressed or contracted to their original size before they can be introduced into the breech of a gun as freely as in the first instance and so used again. Therefore, the first step in the present operation is to re-size the empty shell, and the die *d* and the arm 14 serve this purpose, under force applied through plunger 3 and pinion 4 or their equivalent. Different dies 15 may be employed according to the size and 20 shape of the shells and the tapered shells are introduced with their taper downward.

The next step in the operation is to remove the dead cap or primer from the shell while the shell is held tightly within the 25 die, and this is accomplished by means of arm 15 and a vertical rod or stem 18 affixed in said arm and which has a shouldered and reduced upper extremity *n* adapted to enter a small hole in the head of the shell beneath 30 the primer *c* therein and in so doing to forcibly eject the primer as illustrated in Fig. 3. As this occurs the shoulder at the base of the reduced extremity *n* will engage the inner bottom of the shell and lift and 35 release the shell from the die, also as appears in Fig. 3. In this latter operation the thrust of shaft 3 is reversed through pinion 4, the parts raised to the limits of slots 10 and 11, and the loose shell removed by hand.

40 The empty and de-capped shell is now ready for repriming or capping and filling with powder, and priming precedes filling as a precaution against possible premature explosion. This introduces other elements 45 having a co-acting relation with and dependent upon the operation of plunger shaft 3 and the pinion 4. Thus, a turret 20 is rotatably mounted on a stud shaft 26 fixed upon a lateral projection 21 near the bottom 50 of the standard 2, and a spring pressed detent 23 socketed within the upper face of projection 21 is adapted to enter the cavities 24 in one side of the turret to limit the rotations thereof in a step-by-step movement, 55 and because the turret is invertible or reversible according to the successive steps in the work to be done therein, I also provide a circle of cavities 24' in the plate 27 which covers the side of the turret.

60 Thus, in Fig. 3, the turret is in position to reprime or cap the shells, which are placed in the two circles of bores or pockets 25 formed in the turret and shaped to the contour of the shells, and the said pockets agree 65 in registration and position with the cavities

24. Each pocket is of a depth corresponding to the length of the shell, plus a reduced extension to receive the elongated bullet 40, and a plate or disk 27 on one side of the body of the turret 27 has perforations 28 in two 70 circles corresponding to the shell pockets 25 and adapted to come centrally over the same. The plate or disk 27 is secured upon a bearing sleeve 29 engaged over the central shaft 26 which is fixed in projection 21 and upon 75 which the turret rotates, and said sleeve is secured by a ring nut 30 on the opposite side of the turret.

The primer *c* corresponds substantially to the diameter of the perforations 28 in disk 80 27 and also to the cavities in the heads of the shells, and hence, assuming that a live primer is placed over or within a perforation 28, a suitable plunger will be sufficient to force it into the cavity coinciding in position thereto in the shell. Two thrust plungers 85 33 are provided for this purpose, which are set into a rotatable head 34 on a short horizontal shaft 35 fixed in the rack bar or shaft 3 through slot 9 in the standard 2. Head 90 34 is preferably spring pressed on one side and slidably mounted on said shaft to afford quick locking and unlocking of the head so that it may be rotated and its position reversed relatively to the turret, a pin 36 in 95 the shaft being adapted to engage either of the radial slots 37 in the head according to which position it occupies. To explain further, two sets of plungers are mounted radially opposite on head 34, and either set of 100 plungers may be positioned so as to work simultaneously with the resizing of the shell in the die *d* first above described. Thus, the plungers 33 may be set to press the primers into the shell heads, or the other set of plungers 105 42 on the head may be placed to press and fix the bullets 40 in the open reduced ends of the shell. But before the bullets and shells are assembled the powder is introduced into the shell. To this end the turret 110 is inverted on shaft 26 after priming operations are finished and the open end of the shell is thereby exposed to receive the powder and bullet. Inverting the turret also places the plate 27 below to serve as a support for 115 the shells when the bullet is driven into the opposite end.

A material benefit and advantage comes to the marksman in refilling the shells himself because it enables him to choose the 120 quality or kind of power he wants and to measure the charges with the most exact nicety and uniformity so that all the shells are charged exactly alike in these particulars. Then when the shells are filled, the 125 final step is to insert the balls or bullets 40 therein. The extension of the pockets in the turret beyond the shell ends enables the bullets to be seated quickly in alignment with the shells and in position for forced 130

23

1,474,355

8

entry into the shells. The force required is imparted by the plungers 42 fixed in head 34, and these plungers have cavities in their ends to receive the pointed or rounded ends of the bullets and to center or align the bullets relatively to the shell. The bullet is pressed home by a down stroke of head 34 and the reciprocable shaft 3 as hereinbefore described, and the parts may be set and arranged to enter a bullet simultaneously with the driving of the shells into the dies to reshape the same.

The disk 27 on the turret has a slot 44 extending radially thereof across both circles of pockets 25 for the shells, and the shells are placed in the turret and removed through this slot. A spring pressed bolt 45 in the turret body also projects through said slot and serves to lock the disk against independent rotation after the shells have been introduced through said slot successively. Locking of the plate locks the shells in place within the turret and none can drop out upon inverting the turret. Unlocking of the plate and rotation thereof must occur to remove the shells. However, the plate may be made as a separate detachable plate and locked in place in any suitable way.

30 What I claim is:

1. A machine for renewing used cartridges, comprising a reciprocating device having a primer pressing plunger and a bullet pressing plunger, in combination with means for supporting a shell in reversely-related positions opposite said plungers.

2. A machine for renewing used cartridges, comprising an invertible holder for shells, and a reversible head having separate primer and bullet pressing members movably related to said holder opposite the shells therein.

3. A machine for renewing used cartridges, comprising a rotatable shell holder, in combination with a reciprocable device having a set of presser members rotatably mounted opposite the shell in said holder.

4. A machine for renewing used cartridges, comprising a turret having a rotatable plate detachably connected therewith for confining the shells therein and adapted to be rotated independently of said turret, said plate having guide openings to introduce priming caps to said shells.

5. In a machine for renewing cartridges, a die for reshaping cartridge shells, a hollow upright standard having a slot and a side projection in line with said slot in which said die is removably supported, and a reciprocating plunger in said standard having an arm operating in said slot adapted to bear on the end of a cartridge and force it into the die.

6. In a machine for renewing cartridges, 65 a tubular standard having a die support-

ing projection at its outside and slots lengthwise above and below said projection, in combination with a reciprocable plunger in said standard and arms thereon extending through said slots, a shell re-shaping die 70 in said projection in line with said arms and means to limit the downward thrust of said plunger, the upper of said arms being adapted to force a shell into the die, and means on the lower arm to eject the shell. 75

7. In a machine for renewing cartridges, a tubular standard having a lateral projection and a turret mounted thereon having a series of pockets shaped to receive decapped cartridge shells, means to check said 80 turret step-by-step in rotation, and means to force primers into the said cartridges comprising centering means for the caps and a plunger to force the caps into the shells. 85

8. In a machine for renewing cartridges, a rotatable turret having a series of vertically disposed pockets extending through the same and shaped to receive cartridge shells and a plate over one side of said 90 turret having perforations coincident with said pockets and of a size to insert priming caps therein said plate being affixed in rotatable connection with said turret.

9. In a machine for renewing cartridges, 95 a standard and a reciprocable plunger in said standard, a turret rotatably mounted on one side of said standard and having a series of pockets adapted to receive cartridge shells, means locked to said turret 100 and adapted to carry therewith and center live primers over said pockets and a thrust device supported on said plunger and adapted to force the primers downward through said centering means. 105

10. In a machine for renewing cartridges, an invertible turret having concentric circles of separate pockets adapted to receive cartridge shells, a separate plate affixed to one side of said turret and invertible therewith 110 to support said shells in the pockets, and means to force bullets into a plural number of the shells simultaneously.

11. In a machine for renewing cartridges, an invertible turret having pockets for cartridge shells reduced in diameter at one end having greater length than the shells and correspondingly formed, and means to force bullets into the shells in said pockets comprising a reciprocable plunger, a rotatable head supported on said plunger radially above said turret and a thrust member on said head having a cavity in its end adapted to engage over the point of the bullet and to force the bullet into the shell. 115 120 125

12. A machine for renewing cartridges, having an invertible rotatable turret provided with a series of pockets open on both sides thereof and shaped to the contour of a cartridge shell, in combination with a 130

rotatable head having opposite projections, fix live priming caps within certain of said shells simultaneously with the contraction ¹⁰ of other of said shells.

13. A machine for renewing cartridges,
5 comprising a die and means to contract a used and expanded shell and to remove a dead priming cap therefrom, a turret adapted to receive said shell, and means to

Signed at Cleveland, in the county of Cuyahoga and State of Ohio, this 29th day of January, 1918.

WILLIAM D. FRASER.
